(57) **CLAIM**

The ornamental design for a cell culture bag as shown and described.

DESCRIPTION

FIG. 1 is a front view of a cell culture bag showing my new design;

FIG. 2 is a rear view thereof;

FIG. 3 is a right side view thereof, a left side view being symmetrical to the right side view thereof;

FIG. 4 is a plan view thereof;

FIG. 5 is a bottom view thereof;

FIG. 6 is a perspective view thereof;

FIG. 7 is a partial enlarged view taken from area 7 in FIG. 4;

FIG. 8 is an enlarged cross-sectional view along the line 8-8 in FIG. 7; and,

FIG. 9 is an enlarged cross-sectional view along the line 9-9 in FIG. 4.

1 Claim, 5 Drawing Sheets
